United States Patent Office

Des. 189,396
Patented Dec. 6, 1960

189,396

PLAYGROUND CLIMBER

Robert S. Wormser, Mexico, Pa., assignor to The Mexico Forge, Inc., Mexico, Pa., a corporation of Pennsylvania

Filed Aug. 10, 1960, Ser. No. 61,688

Term of patent 14 years

(Cl. D34—5)

The single figure is a perspective view of a playground climber, showing my new design. The dominant features of the design are shown in full lines.

I claim:

The ornamental design for a playground climber, substantially as shown and described.
